UNITED STATES PATENT OFFICE

VICTOR RAPHAEL ABRAMS, OF BRUNSWICK, GEORGIA

TOBACCO PIPE

Application filed April 29, 1931. Serial No. 533,831.

My invention relates to pipes for smoking-tobacco. It has for its purpose to provide a construction embodying the principle of the Venturi tube which produces a stronger impetus to the passage of smoke from the pipe bowl to the mouth-piece or tip of the pipe and also induces a return flow of smoke and products of condensation from a chamber wherein nicotine and other condensed tobacco-extracts are deposited and from which they are carried by the enforced circulation into another chamber wherein they are collected, and the circulating gases are lowered in temperature and reintroduced into the smoke conduit leading from the pipe bowl and delivered through and from the mouth-piece or tip of the pipe stem, the object being to prevent nicotine reaching the mouth of the smoker through the mouth-piece or tip of the pipe stem, and also provide a cooler smoke, and provide a pipe in which fouling of the pipe is less likely to occur from the nicotine and other fluids coming in contact with tobacco in the bowl, and in which the best tobacco flavours are obtainable.

To the accomplishment of the foregoing and such other objects as may hereinafter appear the invention consists in the features hereinafter particularly described and then sought to be clearly defined by the claims, reference being had to the accompanying drawing forming a part hereof, and in which

Figure 1 is a vertical longitudinal section through a pipe containing the preferred embodiment of the invention;

Figure 2 a longitudinal section through a portion of the stem, on an enlarged scale;

Figure 3 a cross section on the line 3—3 of Figure 2, looking in the direction of the arrows;

Figure 4 a longitudinal section showing a modified form;

Figure 5, a similar section through another modification, on an enlarged scale.

In the drawing the numeral 1 designates a pipe bowl; 2 its stem, and 3 its mouth-piece or tip. The stem is formed with a longitudinally internal chamber 4. Within the chamber is positioned a longitudinally extending

tube 5 having one end threaded or otherwise attached to make a tight joint with the base of the bowl and with which it is in communication. The other end of the tube is provided with a disk 6 which functions as a partition set back from the adjacent end of the pipe mouth-piece or tip so as to form a chamber 7, the disk or partition having a diameter substantially that of the chamber 4 and has in its periphery a notch of opening 8 which establishes communication between the chambers 4 and 7. The tube 5 is restricted adjacent one end so as to make in effect a "Venturi tube", and is formed with an orifice 9 so as to establish communication between the tube and chamber 4. The disk 6 and end of the tube 4 may be made with a kerf 10 to receive the end of a screw-driver to thread the end of the tube into the base of the bowl 1. Under the construction described when suction is created in the tube 5, by inhaling through the bore of the mouth-piece 3, smoke from tobacco in bowl 1 is drawn through tube 5, and at the same time more or less vacuum is created in chamber 4 by the air drawn therefrom through orifice 9 into tube 5 and ejected from tube 5 into chamber 7 under substantially the Venturi principle. In chamber 7 the nicotine and other substances of a volatile nature are deposited and the flavors of the tobacco in the bowl delivered to the smoker deprived of the nicotine and other objectionable tobacco extracts. The nicotine and other tobacco extracts deposited in chamber 7 pass from that chamber into chamber 4, their passage into chamber 4 being promoted by the vacuum in that chamber and the suction exerted through tube 5. The chamber 4 serves as a storage or collecting chamber for the nicotine and other volatile substances deposited in the settling chamber 7 until it is desired to remove deposits from chamber 4 which may be done by turning the pipe, stem down, and jarring or shaking the pipe, either with the mouth-piece in place or removed. In a pipe made as described, tobacco in the bowl is kept in a dry condition, as it is free from moisture to be derived from nicotine or other fluids and with the result that a purer and sweeter

smoke is obtainable; and nicotine and other distasteful concentrates are prevented from passing into the mouth of the smoker through the mouth-piece of the pipe because they are

5 deposited in the settling chamber 7 and finally transferred to the storage or collecting chamber 4, under the influence of suction and vacuum as before mentioned.

The construction illustrated in Figure 4 10 is substantially the same as shown in Figures 1 and 2 of the drawing except that the tube 4 is without the restricted portion as in Figures 1 and 2, and the threaded end of the tube is screwed into a screw-plug 11 threaded 15 into the base of the pipe bowl.

In the modification shown in Figure 5, the smoke conducting tube 5, leading from the pipe bowl, instead of having an orifice in its wall at the end next to the mouth-piece of the 20 pipe has an orifice in it adjacent the end that is attached to the bowl, and a pipe 12 leads from it towards its other end where it opens into the chamber 4, and another pipe 13 leads from the settling chamber 7, and opens into 25 chamber 4 at a point adjacent to the pipe bowl as illustrated.

In this modification the disk or partition 6^a is formed with a port 14 provided with a valve 15 which will be normally closed by 30 contact of the end of mouth-piece 3 therewith as shown, the stem 16 of the valve being formed with a head 17 having projections 18 on one face, so that when the mouth-piece is removed for cleaning chamber 4 the valve 35 will open and the projections 18 will space the head from the port so that the fluid contents of the chamber 4 may be discharged through the port. Otherwise however the operation is substantially the same as in the 40 other forms.

I have illustrated and described with particularity details of the features embodied in several modifications of the invention but it is to be understood that the features may 45 be otherwise varied and that I am not limited to such details except as the same may be expressed in the appended claims.

Having described my invention and set forth its merits, what I claim is:

50 1. In a tobacco-pipe comprising a bowl for tobacco, a pipe stem, and a mouth-piece, the stem being formed with a longitudinally disposed chamber; a smoke conducting tube having an opening therein, positioned within 55 said chamber and in communication with the bowl of the pipe (and a diaphragm partition, having an opening therein, positioned at one end of said tube to form a settling chamber between the partition and adjacent end of 60 the mouth-piece in communication with the chamber of the pipe stem, the smoke conducting tube also being in communication with the chamber of the pipe stem, whereby suction through the smoke conducting tube creates 65 circulation of gases between the settling

chamber and chamber of the pipe stem, and condensable products are intercepted in the settling chamber and may be transferred to the chamber of the pipe stem.

2. In a tobacco-pipe comprising a bowl for 70 tobacco, a pipe stem, and a mouth-piece, the stem being formed with a longitudinally disposed chamber; a smoke conducting tube positioned within said chamber in communication with the bowl of the pipe and having 75 an opening therein in communication with the chamber and a diaphragm partition positioned at one end of said tube to form a settling chamber between the partition and adjacent end of the mouth-piece whereby suction 80 through the smoke conducting tube creates circulation of gases between the settling chamber and chamber of the pipe stem and condensable products are intercepted in the settling chamber, said diaphragm being provided with a valve-controlled port for controlling communication between the settling chamber and chamber of the pipe stem through said port.

3. In a tobacco-pipe comprising a bowl for 90 tobacco, a pipe stem, and a mouth-piece, the stem being formed with a longitudinally disposed chamber; a Venturi tube having an 95 opening therein and positioned within the chamber and in communication therewith and with the bowl of the pipe to constitute a smoke conducting tube, and provided with an enlargement at one end to form a settling chamber between it and the adjacent end of the mouth-piece, said enlargement having an 100 opening, whereby suction through the tube creates circulation of gases between the settling chamber and chamber of the pipe stem and condensable products are intercepted in the settling chamber, whereby said 105 settling chamber has communication with the chamber in which the Venturi tube is positioned through the opening in the enlargement.

In testimony whereof I affix my signature. 110
VICTOR RAPHAEL ABRAMS.
